CROWN BLOCK

Filed June 11, 1929

UNITED STATES PATENT OFFICE

HARRY P. WICKERSHAM, OF WALNUT PARK, CALIFORNIA, ASSIGNOR TO BAASH-ROSS TOOL COMPANY, INCORPORATED, OF LOS ANGELES, CALIFORNIA, A CORPORATION OF CALIFORNIA

CROWN BLOCK

Application filed June 11, 1929. Serial No. 370,111.

This invention has to do with a crown block, and it is an object of the invention to provide a crown block for use on a derrick, such as a well derrick, or the like, that is simple, practical and of improved construction.

It is an object of the present invention to provide a construction for a crown block whereby the sheave carrying bearings are shiftable or adjustable in two directions and can be set or secured firmly for operation.

It is another object of the invention to provide a bearing mounting for a crown block that is effective in supporting a number of shafts so that they are always in the proper relation to one another and are shiftable or adjustable as a unit.

Another object of the invention is to provide a simple, practical and improved frame construction for a crown block.

A further object of the invention is to provide a cover for a crown block for a well drilling rig. The cover construction provided by the invention protects or shields the sheaves and is easily operated to allow access to the sheaves when necessary.

It is another object of the invention to provide a sectional crown block in which the sections are supported independently from the derrick and are connected so that they cannot become independently displaced from the derrick.

The various objects and features of the invention will be best and more fully understood from the following detailed description of a typical form and application of the invention, throughout which description reference will be had to the accompanying drawings, in which:

- 40 Fig. 1 is a side elevation of the crown block provided by this invention. Fig. 2 is an end view of the crown block showing the sheave cover in the down position. Fig. 3 is an end view of the upper portion of the crown block showing the sheave cover in the up or open position. Fig. 4 is an enlarged vertical detailed sectional view taken as indicated by line 4-4 on Fig. 2. Fig. 5 is an enlarged detailed vertical sectional view taken as indicated by line 5-5 on Fig. 1. Fig. 6 is an enlarged sectional view taken on line 6-6 on Fig. 3.
- 45 The crown block provided by this invention is designed primarily for use in the derrick of a well drilling rig. In the drawings I have shown the crown block mounted on the rectangular frame or head 10 at the top of a typical form of well derrick 11.
- 50 The device provided by this invention is intended to be mounted directly on the head 10 of the derrick, and includes, generally, two sheave supporting sections A and B. The section A, which may be termed the lower section, is adapted to be carried on two opposite side members of the head 10, while the section B, which I will term the upper section, is intended to be mounted on the other two side members of the head 10. The section B extends transversely over or straddles the lower section A.
- 55 The lower section A includes, generally, a frame 12 which rests directly upon the head 10, a plurality of sheaves 13, and bearings 14 mounting the sheaves on the frame. The frame 12 is preferably formed of a plurality of spaced beams 15 extending between opposite side members of the head 10. The beams 15 are connected together by spacer blocks 16 which secure the ends of the beams together to form a rigid frame construction. The 60 bearings 14 are mounted on the tops of beams and are arranged so that they support the sheaves 13 in vertical positions between the beams 15, as clearly shown in Fig. 2 of the drawings. The bearings 14 are connected to the beams 15 by means of clamps 16^a and studs 17 which extend from the clamps to the bearings. The clamps 16 engage the under sides of the top flanges of the beams 15. When the nuts 18 on the studs 17, which engage the caps 19 of the bearings 14, are tightened, the clamps 16 are drawn upwardly and the caps 19 are held in place on the bearings. With this arrangement the bearings 14 may be loosened and then shifted or adjusted along the tops of the beams 15 to locate the sheaves as desired. It is to be understood that the sheaves 13 may be of any desired diameter and width and that the spacing of the beams 15 may be related to the 65 70 75 80 85 90 95 100

width of the sheaves 13 so that proper clearance is allowed between the beams and the sheaves.

The upper section B of the crown block includes, generally, base members 21 adapted to rest on the head 10 of the derrick, blocks 22 adjustably supported on the base members, beams 23 extending transversely between the blocks, bearing units 24 shiftably supported on the beams, a shaft 25 carried by bearings of the units 24 to extend transversely between the beams, a plurality of sheaves 26 carried on the shaft, spacer plates 27 between the sheaves, supporting rods 28 for the spacer plates carried by the bearing units 24, and a cover 30 for the sheaves.

The base members 21 are in the form of I beams and are adapted to be mounted on opposite side members of the head 10. The 20 side members which support the base members 21 extend between the side members of the head 10 that support the beams 12 of the section A. The base members 21 are arranged with their lower flanges extending 25 longitudinally on the side parts of the head 10. The base members are parallel to the beams 12 of the section A.

The blocks 22 of the section B are mounted on the base members 21 to be adjusted or shifted longitudinally of the base members 21. The blocks 22 are preferably formed of I beams and are arranged on the upper flanges 31 of the base members. The lower flanges 32 of the blocks 22 rest directly on the upper flanges 31 of the base members. Each block 22 is connected to a base member 21 by pairs of clamps 33. In the preferred form of the invention the two clamps of each pair are arranged at opposite sides of the block and each 40 clamp has an upper end part engaging the web 22^a of the block 22 and a lower jaw portion 39 receiving the abutting flanges 31 and 32 of the base 21 and block 22, respectively. A bolt 34 is arranged in connection with each 45 pair of clamps to extend through an opening 35 in the block 22 and through openings 36 in the clamps. A nut 38 is threaded on the end of the bolt to clamp the clamps onto the web 22^a and the flanges 31 and 32. The jaw portion of each clamp 39 is formed so that it wedges onto the flanges and clamps them tightly together. With the blocks and the base members connected in this manner, the nuts 38 can be loosened, allowing the sheaves 50 55 26 to be adjusted along the base members 21. When the nuts 38 are made tight, the blocks 22 are securely and rigidly connected to the base members 21.

In the preferred form of the invention, 60 means is provided for shifting the block members 22 on the base members when the nuts 38 are loose. In the drawings I have illustrated the blocks as being somewhat shorter than the base members 21, and have 65 shown adjusting screws 40 threaded through

brackets 41 fixed on upper faces of the flanges 31. The screws 40 engage the ends of the blocks 22.

An adjusting screw 40 is provided at each end of each base member 21 so that the blocks 22 can be urged in either direction and can be set in the desired position longitudinally of the base members as well as being set by tightening the clamps 33.

The beams 23 of the section B extend transversely between the blocks 22 and extend transversely of and are above the beams 12 of the section A. The base members 21 and the block members 22 elevate the beams 23 a substantial distance above the beams 12. The 75 beams 23 are preferably I beams and may be supported from the blocks by brackets 42. The brackets 42 have vertical flanges 42^a that are connected to the webs 22^a of the blocks 22 by bolts 42^b. A horizontal flange 42^c extends along the upper edge of each bracket 42. The flanges 42^c engage the undersides of the lower flanges of the beams 23 and may be connected to the beams by bolts 43^a. A bracket 42 may be provided at each end of each beam 80 85 90 95 23. The distance between the shaft of section A and the lower edges of the beams 23 may be changed or varied by using different sized brackets 42. By replacing the brackets 42 with brackets that support the beams 23 so that they are elevated to positions substantial distances above the blocks 22, larger sheaves may be used in the lower section A. With the arrangement just described it is possible to use various sized sheaves in the section A 100 without materially altering the construction of the crown block and without raising or lowering the entire section B. End plates 43 are provided to space the beams 23 apart and lend rigidity to the structure.

The bearing units 24, which carry the shaft 25 and the rods 28, are arranged opposite each other on the beams 23 and are mounted so that they are adjustable longitudinally of the beams. The bearing units 24 carry the shaft 25 and the rods 28 so that they are disposed above the section A in parallelism with the beams 12 of the section A. In accordance with my invention, there is but one bearing unit 24 on each beam 23. The bearing units 24 carry the shaft and the rods so that the shaft 25 is located between the rods 28, the rods being beyond the sheaves carried by the shafts.

Each bearing unit 24 consists of a base portion 44 resting directly on the beam 23, three spaced bosses 45 on the base, and webs 46 joining the base and extending between the bosses. The base 44 is flat and adapted to be secured to the top of a beam 23. In the form of the invention illustrated the bosses 45 are spaced on the base so that there is a boss at each end of the base to receive a rod 28 and a boss at the middle of the base to receive 105 110 115 120 125 130 135 140 145 150 155 160 165 170 175 180 185 190 195 198 200 205 210 215 220 225 230 235 240 245 250 255 260 265 270 275 280 285 290 295 298 300 305 310 315 320 325 330 335 340 345 the shaft 25. Openings are provided in the bosses to carry the shaft or rods.

Each bearing unit 24 is mounted so that it is shiftable longitudinally on its supporting beam 23. In the case illustrated longitudinal slots 50 are provided in the base 44 and bolts 51 extend through the slots and through the top flange 54 of the beam 23. Clamping nuts 51^a are screw threaded on the bolts 51 to clamp or set the base 44 on the beam.

The invention provides means for adjusting the bearing units longitudinally of the beams when the nuts 51^a are released. In the case illustrated the bearing units are shorter than the beams and adjusting screws 60 are carried by brackets 61 to engage the ends of the units. The brackets 61 are attached to the top flanges of the beams and the screws are threaded through the brackets. There is an adjusting screw at each end of each beam or unit.

The sheaves 26 are rotatably mounted on the shaft 25 and are spaced apart by the spacer plates 27. The plates 27 act to support the shaft between the sheaves, the plates being carried by the rods 28 supported by the bearing units. The plates 27 are arranged vertically and project horizontally in each direction beyond the sheaves. The end portions of the plates beyond the sheaves are carried by the rods 28. The plates 27 extend upwardly and inwardly from the points of connection with the rods 28 to a point above the sheaves, and have their upper portions connected and braced by a bolt 55 which extends over the sheaves. Spacing washers 66 are provided on the rods 28 to hold the plates 27 in spaced relation and spacing sleeves may be provided on the bolt 55 between the plates. Nuts 26^a on the ends of the rods outside of the bearing units hold the parts assembled. A similar nut 28^b is provided on the shaft 25.

The cover 30 is mounted on the plates 27 to extend over and protect the sheaves 26. In the preferred form of the invention the cover is pivotally connected to the end portions of the plates 27. The cover 30 is formed to have the configuration of the top or upper portions of the plates 27, that is, it has two main parts 70^a extending outwardly and downwardly from the tops of the plates to their end portions and which extend across the assembly from one end plate to the other. The cover is attached to the plates by two pivot bolts 70, one extending transversely through the plates 27 at each end of the cover. By removing one of the pivot bolts 70, the cover may be pivoted on the other bolt to a position as illustrated in Fig. 3 of the drawings. In this manner the cover 30 may be swung to either side of the construction as desired. The cover 30 is provided at its side edges with side parts or flanges 71 which extend downwardly to overhang the two end plates 27. In the particular case illustrated the pivot

bolts 70 extend through the flanges 71 as clearly shown in the drawings.

There is a connection provided between the sections A and B of the construction so that the sections cannot become accidentally separated. It is preferred that this connection be such that it does not interfere with the independent mounting or support of the sections directly on the head of the derrick.

I may provide a rod 80 between the base members 21 to extend through openings in the webs of the beams 12. The rod is preferably located near one end of the section B at a point where it will not interfere with the lines carried by the block. The openings in the webs of beams 12 may be large enough to freely pass the rod so that there is no direct connection between the two sections of the block.

In using the crown block provided by this invention it is possible to adjust the sheaves to various positions through the adjustable connection between the base members 21, and the block members 22 and the adjustability of the bearing units 24. When the sheaves are in the desired positions the various parts may be set, making the structure ready for use. It will be obvious that the sections A and B can be removed and handled independently of each other, it being possible to move either of the sections independently of the other when the rod 80 is removed. When the block is in use the rod 80 connects the sections so that they cannot be accidentally separated, for instance, so that the lower section is not freed from the derrick if the traveling block runs into the lower section and lifts it from the derrick parts which normally support it.

Having described only a typical, preferred form of the invention, I do not wish to limit myself to the specific details set forth, but wish to reserve to myself any changes or variations that may appear to those skilled in the art or fall within the scope of the following claims.

Having described my invention, I claim:

1. A crown block including, spaced base members to be mounted directly on a derrick, blocks adjustably supported on the base members, spaced beams extending between the blocks, sheaves, a shaft supporting the sheaves, spacer plates between the sheaves, a rod supporting the spacer plates, and unitary members on the beams supporting the shaft and rod.

2. A crown block including, beams to be mounted on a derrick, sheaves, rods, a shaft supporting the sheaves, and unitary members on the beams supporting the shaft and rods.

3. A crown block including, beams to be mounted on a derrick, sheaves, a shaft supporting the sheaves, a rod, plates engaging the rod and shaft, and unitary members on the beams supporting the shaft and rod.

4. A crown block including, beams to be

- mounted on a derrick, sheaves; a shaft supporting the sheaves, a rod, unitary members on the beams supporting the shaft and rod, and means for attaching the members to the beams. 5 means whereby the bearings may be adjusted on the supports, said means including bolts projecting from the supports and extending through slots in the bearings, and clamping nuts on the bolts for engaging the bearings. 70
5. A crown block including, spaced base members to be mounted on a derrick, blocks adjustably supported on the base members, clamp means connecting the base members 10 and the blocks, beams supported on the blocks; a shaft supported by the beams, and a sheave on the shaft. 15 75
6. A crown block including, spaced supports to be mounted on a derrick, a shaft carried by the supports, a plurality of sheaves on the shaft, spacer plates between the sheaves, and a cover for the sheaves carried by the plates. 20 80
7. A crown block including, spaced supports; a shaft carried by the supports, a plurality of sheaves on the shaft, spacer plates between the sheaves, and a pivotally mounted cover for the sheaves. 25 85
8. A crown block including, spaced supports; a shaft carried by the supports, a plurality of sheaves on the shaft, spacer plates between the sheaves, a cover for the sheaves, and two spaced releasable pivotal connections between the cover and the plates. 30 90
9. In a crown block, two sections for independent mounting on a derrick, sheaves supported on each of the sections, and means connecting the sections against separation. 95
10. A crown block including, two sheave supporting sections for independent mounting on a derrick, and a rod connecting the sections against separation. 100 105
11. A crown block including, two sheave supporting sections for independent mounting on a derrick, and a connection between the sections holding them against separation. 110
12. A crown block including spaced base members to be mounted directly on a derrick, blocks adjustably supported on the base members, beams extending between the blocks, sheaves; a shaft supporting the sheaves, spacer plates between the sheaves, a rod engaging the spacer plates, unitary members adjustable on the beams and supporting the shaft and rod, and screw means for adjusting the members. 115
13. A crown block including spaced supports, a shaft, sheaves on the shaft, a rod spaced from the shaft, spacer plates between the sheaves carried by the shaft and rod, a single bearing on each support carrying an end of the shaft and an end of the rod, and means whereby the bearings may be adjusted on the supports. 120
14. A crown block including spaced supports, a shaft, sheaves on the shaft, a rod spaced from the shaft, spacer plates between the sheaves carried by the shaft and rod, a single bearing on each support carrying an end of the shaft and an end of the rod, and 125 130
